DESIGN FOR AN ELECTRIC LIGHT FIXTURE

Stephen P. Holish, Chicago, Ill.

Application February 5, 1940, Serial No. 90,046

Term of patent 3½ years

To all whom it may concern:

Be it known that I, Stephen P. Holish, a citizen of the United States and a resident of Chicago, county of Cook and State of Illinois, have invented a new, original, and ornamental Design for an Electric Light Fixture, of which the following is a specification, reference being had to the accompanying drawing, forming a part thereof.

Figure 1 is a perspective view of an electric light fixture showing my new design.

Figure 2 is a front elevational view thereof.

Figure 3 is a rear elevational view thereof.

Figure 4 is an enlarged end view of an electric light fixture with one end plate removed for the purpose of showing the corrugated arcuate reflector forming a part thereof.

I claim:

The ornamental design for an electric light fixture, substantially as shown.

STEPHEN P. HOLISH.
